UNITED STATES PATENT OFFICE.

WILLIAM C. BOSWELL, OF BALTIMORE, MARYLAND.

ELECTRIC SADIRON.

Application filed June 14, 1922. Serial No. 568,127.

To all whom it may concern:

Be it known that WILLIAM C. BOSWELL, a citizen of the United States, residing at Baltimore, in the State of Maryland, has invented certain new and useful Improvements in Electric Sadirons, of which the following is a specification.

This invention relates to improvements in sad irons and has particular reference to an iron that is to be electrically heated.

An object of the invention is to provide an iron embodying novel features in construction, which will facilitate its assembly; retain the heat at its ironing surface and will withstand jars and knocks that ordinarily put an electric iron out of commission.

Another object of the invention is to provide an iron having an improved filler for carrying the heating wires whereby the latter may be removed and new wires installed.

With these, and other objects in view, the invention is illustrated in the accompanying drawings, wherein,—

Fig. 1. shows the complete iron in side elevation.

Fig. 2. illustrates a cross-sectional detail through the same,—the section being taken on the line 2—2 of Fig. 1.

Fig. 3. shows another sectional detail through the iron,—the section being taken on the line 3—3 of Fig. 1.

Fig. 4. illustrates the detached filler-block in bottom view to show the wire-receiving cavities therein.

Fig. 5. shows the same block with the wires placed in the cavities thereof and the cavity partly filled with a filling composition.

Fig. 6. illustrates the handle and iron casting in longitudinal section.

Fig. 7. shows the detached insulator shell in longitudinal section, and

Fig. 8. illustrates the ironing plate and filler-block, the same being sectioned at one end to show the binding posts therein.

Referring to the drawings the numeral 10, designates the smoothing or ironing-plate which latter has a plurality of screw-threaded sockets 11 on its upper side for a purpose presently to be described.

On the upper side of the ironing-plate I seat a filler-block 12 which is of less width and length than the upper surface of the ironing-plate so that, when seated thereon,

the ironing-plate will project slightly all the way around the base and form a support or shoulder 13.

This filler-block 12 has novel features in that, although it is preferably formed of soapstone, it is baked and hardened and is thus made tough so that it will withstand knocks and jars and will not crack or crumble as do the ordinary soapstone fillers usually employed in irons of this character. The baking and hardening of this filler has other useful objects in view that will presently be explained.

By reference to Figs. 2—3—4—5 and 8 of the drawings it will be seen that the filler-block 12, has a flat supporting surface 14 which seats on the flat top surface of the ironing-plate 10 and also has a flat top-surface 15. The supporting surface, which is also the bottom, is both wider and longer than the top surface while the two sides 16 are tapered or sloping and converge as they extend forwardly where they form a point 17.

The rear edge 18 of the filler-block is broad in a cross-wise direction and also tapers or inclines. The sloping rear and side edges of the filler-block have a useful function when the parts are assembled as will presently appear.

The bottom of the filler-block is provided with a recess 19 in which there are a plurality of spacing webs, flanges or projections 20 whereby to form a series of wire-receiving channels 21.

The heating wire 22 is laid in the channels 21 in such manner that the stretches thereof are kept separated, one from another, by the webs, flanges or projections, as clearly shown in Fig. 5 of the drawing while the two ends of the wires are connected to two binding-posts 23 and 24 respectively. These binding-posts extend in an inclined direction through the filler block and incline rearwardly as they extend upwardly above said block. The upper side of the filler-block is provided with an end-edge notch or recess 25 the forward edge 26 of which slopes upwardly so as to extend at a right angle to the axes of the posts 23 and 24 so that binding-nuts 27 may be screwed onto the posts and clamp the posts in place. By providing the recess 25 the upper nuts will have a countersunk position below the upper surface of the block and

will not interfere with the seating of another part that is to be placed on top of the block.

After the wires 22 are in place in the 5 filler-block I fill the bottom recess and channels with composition or cement which will seat so that the wires will be completely enclosed and concealed in the bottom of the block. This is desirable because, in case the 10 wire burns out, this filler or composition may readily be gouged out and the old wire then removed and a new one substituted without injury to the filler-block itself, because the latter has been hardened.

15 The filler-block 12 is provided with a plurality of vertical perforations 28, which register with the threaded sockets 11 in the ironing-plate, also for a purpose that will presently be described.

20 In the further construction of my iron I provide an insulator shell 29 of asbestos. This shell is shaped to snugly fit down over the top of the filler-block and has suitable perforations 30 and 31 therein—the latter 25 to permit the passage of the binding-posts and the former registering with the perforations 28 in the block beneath.

The iron also makes use of a metal outer casing 32 which has a recess 33 in its under 30 side with sloping and longitudinally-converging side-walls 34 and a tapered rear wall 35. The interior of this casing recess conforms to the external shape of the shell 29 so that said shell and the filler-block 35 may fit up therein.

Near the rear end, the casing has two inclined passages 36 with a recess 37 at the base thereof so that tubular bushings 38 may extend through said casing and form insulators through which the binding posts may 40 project.

The casing is comparatively thick above the recess 3 so as to provide sufficient weight for the iron, and vertical passages 39 are 45 formed through this thickened part.

The upper side of the casing is provided with a boss 40 around each of the perforations whereby to form a support for a bracket 41, which latter carries a handle 42.

50 When the parts are assembled with the shell 29 on the filler-block and the casing 32 seated down on the shell, the inclined wall 35 of the casing recess seats on the inclined end wall of the shell and forces the 55 shell and filler-block forwardly toward the point-end of the casing-recess while the tapered walls ensure that the several parts will fit close together in a vertical direction.

After the parts are assembled, suitable 60 bolts 43, are passed down through the bracket 41, the passages 39, perforations 30 and 28 and screwed into the recesses 11 in the ironing plate. These bolts draw all the 65 parts together and hold them rigidly in place.

A suitable socket guide 44, is attached to the rear of the bracket 41 and the upper ends of the binding post terminate in this guide so that the socketed-end 45, of an electric connection, shown in broken lines in 70 Fig. 1, may readily be inserted in the guide and engaged with the posts.

Having described my invention, I claim,—

1. In an electric sad iron the combination 75 with an ironing-plate of a filler-body seated on the upper side of said plate said body being of a baked soap-stone substance which is hardened by the baking and which is an insulator against the passage of electric current but will retain heat, heating wires in 80 said body to heat the latter, posts extending through said body and in electrical connection with said wires and a metallic casing covering said filler-body and connected to said ironing-plate.

2. In a sad iron the combination with an ironing-plate, of a filler-body of a baked material on said plate but of less area than the latter whereby said plate will project from beneath the body and form a flange 90 or support all the way around the base of the body, said body having a beveled rear end and sloping sides, a heavy metallic casing to provide weight and having a cavity 95 in its under side with a tapered end wall and sloping side walls whereby to fit down over the body of baked material and securing devices passing through the heavy casing and body and engaging the ironing-plate whereby to clamp the body in place.

3. In an electric sad iron the combination 100 with an ironing-plate of a filler-body of a baked soapstone substance which is hardened by the baking and which is an insulator against the passage of electric current said filler body having a recess in its upper rear end and also having a vertical opening therethrough, heating wires in said body to heat the latter, posts extending into the 105 body at said recess and said posts being connected to said wires, a metallic casing having a recess in its bottom to receive the filler-body said casing being thickened above the cavity to provide weight and the thickened portion being provided with openings for 110 the passage of the posts and the metallic body also having a vertical opening to register with the vertical opening in the filler-body, a handle-bracket on top of the metal casing and fastening means extending through the bracket, the thickened portion of the casing and the filler-body and engaging the ironing-plate.

4. In an electric sad iron the combination 115 with an ironing-plate of a filler-body seated on the upper side of said plate said body being of a baked and thereby hardened substance which is an insulator against the passage of electric current but which will retain heat and said body having an edge 120

125

130

notch or recess in its rear upper side, heater wires in said body, posts extending through the body and projecting therefrom at said rear notch or recess, a securing nut on the post which nut is seated in said rear body-recess, a heavy metallic casing having a bottom recess to fit down over the body and means for securing the casing to the ironing-plate.

10 5. In an electric iron the combination with an ironing-plate, of a filler-body of baked and hardened soapstone on said plate and having wire-channels therein and also having sloping sides and a beveled end, wires

in said channels, posts extending through the body in front of the beveled end and connected to said wires, a heat insulating covering over the soapstone body, a heavy metallic casing having a bottom recess which conforms to the shape of the insulating covering, a handle-bracket on top of the heavy casing, and securing devices passing down through the bracket, the casing, the insulator covering and body and engaging the ironing-plate to clamp the several parts together.

In testimony whereof I affix my signature.
WILLIAM C. BOSWELL.
